(57) **CLAIM**

We claim the ornamental design for a power tool, as shown and described.

DESCRIPTION

FIG. 1 is a front perspective view of a power tool, such as a band saw.

FIG. 2 is a rear view of the tool shown in FIG. 1.

FIG. 3 is a front view of the tool shown in FIG. 1.

FIG. 4 is a top view of the tool shown in FIG. 1.

FIG. 5 is a right side view of the tool shown in FIG. 1.

FIG. 6 is a left side view of the tool shown in FIG. 1; and,

FIG. 7 is a bottom view of the tool shown in FIG. 1.

In the present application, the solid lines are used to claim edge lines of the design and the surfaces between the solid lines are not part of the claimed design. The broken line showing of the environment is for illustrative purposes only and forms no part of the claimed design.
